CLAIM

The ornamental design for a limited clearance tool, as shown and described.

DESCRIPTION

FIG. 1. is a top front right side isometric view of a limited clearance tool;

FIG. 2. is a bottom rear left side isometric view thereof;

FIG. 3. is a front elevation view thereof;

FIG. 4. is a rear elevation view thereof;

FIG. 5. is a left elevation view thereof;

FIG. 6. is a right elevation view thereof;

FIG. 7. is a top plan view thereof; and,

FIG. 8. is a bottom plan view thereof.

Evenly spaced dashed lines form no part of the claim.
